UNITED STATES PATENT OFFICE.

PERLIE E. CURTIS, OF BANGOR, MAINE.

ELECTRIC-LIGHT ATTACHMENT FOR LEVELS.

1,121,329.

Specification of Letters Patent. Patented Dec. 15, 1914.

Application filed May 16, 1913. Serial No. 768,176.

To all whom it may concern:

Be it known that I, PERLIE E. CURTIS, a citizen of the United States, residing at Bangor, in the county of Penobscot and State of Maine, have invented certain new and useful Improvements in Electric-Light Attachments for Levels, of which the following is a specification.

My invention relates to new and useful improvements in carpenters' levels, the primary object of my invention being the provision of means for lighting up the bubble tubes of a level in such a manner that the position of the bubble may be readily seen in the dark.

It is well known that in many instances the level must be used in basements and other places where it is too dark to see the bubble without a light and oftentimes these basements are used for the storage of goods of such a nature that it is dangerous to light matches or lamps. Under these circumstances it has been necessary, unless the building is equipped with electric lights so that an extension can be run to the place where the work is being done, to use pocket flash lights. This however, is a disadvantage as both hands of the workman are often employed in holding the level and certain of the timbers which are being positioned and he can not employ the flash light himself, thus requiring the assistance of a helper. To obviate this difficulty I have provided pockets in the body of the level itself to receive a small dry battery and electric lamps, the lamp receiving pockets being so arranged that the light therefrom passes outwardly through the bubble tubes and consequently clearly lights up the bubbles.

In this connection, a further object of my invention is to so arrange the lamp receiving pockets as to render the lamps as effective as possible and at the same time have them accessible for renewal. And a still further object of my invention is to provide a switch for the lighting circuit between the battery and lamps so arranged that it may be readily closed by the operator while holding the level in his hand in the usual manner and further so arranged as to lie entirely within that face of the level to which it is applied in order to offer no obstruction to the use of the level for all purposes.

With these and other objects in view, my

invention will be more fully described, illustrated in the accompanying drawings, and then specifically pointed out in the claims which are attached to and form a part of this application.

In the drawings: Figure 1 is a perspective view of my improved level; Fig. 2 is a side elevation, parts being broken away to permit the showing of the level upon an enlarged scale; Fig. 3 is a perspective view of one of the contacts employed in connection with one of the lamps; Fig. 4 is a similar view of the contact employed in connection with the other lamp.

Corresponding and like parts are referred to in the following description and indicated in all the views of the drawings by the same reference characters.

In the drawings, which show a preferred embodiment of my invention, I have illustrated the lighting system in connection with a conventional form of level 10 formed of wood and having the usual longitudinally extending bubble tube 11 protected by a slotted face plate 12 and the transverse bubble tube 13 which is exposed through a sight opening 14 formed transversely through one end portion of the level, the former bubble tube being used in leveling horizontal timbers and the like, while the latter is used in truing vertical timbers and the like. It will, however, be understood that the lighting system hereinafter to be fully described may be employed with any conventional type of level and also with levels constructed of metal as well as wood, the sole distinction in the latter case being that care must be taken in regard to the insulation of the lighting circuit from the body of the level.

In carrying out my invention I recess that end of the level opposite the bubble tube 13 to provide a battery receiving pocket 15. The inner end of this pocket is further recessed as at 16 for a purpose which will be hereinafter apparent, and the body of the level is then provided with a longitudinally extending bore 17 one end of which communicates with the extended chamber 16 of the pocket 15 and the other end of which terminates at a point slightly short of the bubble tube 13. One of the side faces of the level is then recessed to provide a lamp pocket or chamber 18 adjacent the bubble tube 11 and further recessed to provide a second lamp pocket or chamber 19 adjacent the bubble tube 13. The bore 17 communi-

2
cates with both of these lamp pockets and both pockets are undercut to open out directly beneath their respective bubble tubes. The said face of the level is further recessed as at 20 to receive the push button switch which will be later described, bores 21 and 22 leading to this recess from the pocket 19.

Mounted in the pocket 18 and in alignment with the bore 17 is a spring contact 23 including a body portion provided at one end with a laterally directed perforated ear 24 to receive a screw 25 which also serves as a binding post and having an upwardly and 10 then downwardly bowed free end. A bracket 26 is secured to one wall of the pocket 18 by a screw 27 and this bracket is provided with a threaded socket 28 to receive the threaded plug of a small electric 15 light bulb 29. This bulb, when in place, bears by the contact portion of its plug against the contact 23 and the circuit passes from said contact through the filament of the burner to the socket 28 and bracket 26. 20 A spring contact 30 is secured in the pocket 19 by a screw 31, forming a binding post as will be later explained, this contact, as shown in Fig. 4, includes a body member 25 perforated at one end for the screw and having its opposite end bowed outwardly for 30 engagement against the plug contact for a second light bulb 32 which is supported in a threaded socket 33 of a bracket secured in the pocket 19 by screws 34 also forming 35 binding posts.

Mounted in the recess 20, is a switch including a fixed contact 35 and a spring contact 36 which is fixedly secured by one end and the opposite end of which, because of 40 its resiliency, is normally held slightly out of engagement with the contact 35. This free end however, may, under pressure by the finger of the operator, be moved into engagement with the contact 35.

Seated in the extension 16 of the battery pocket 15, is a removable contact carrying plate or block 37 formed of insulating material and threaded into this block are spaced 45 contacts 38 and 39. A wire 40 connects the contact 38 with the contact 23 being secured to the latter by the screw 25, a wire 41 leads from the contact 23 to the contact 30 being secured thereto by the screw 31, a wire 42 leads from the screw 27 of the bracket 26 50 to one of the screws 34 of the socket forming bracket 33, a wire 43 leads from the opposite screw of this socket bracket to the movable switch contact 36 and a wire 44 leads from the fixed contact 35 of the switch back to the contact 39. A dry cell 45 of any suitable 55 type, such as is commonly used in pocket flash lights, is positioned in the chamber 15 and this pocket or chamber is so proportioned and the contacts 38 and 39 so arranged 60 that the spring terminals 46 and 47 65 ranged that the spring terminals 46 and 47

of the battery, when the latter is in place, are held against the contacts 38 and 39, respectively.

The light bulb receiving pockets are normally closed by cap plates 48 and 49 which 70 are formed to lie flush with the face of the level and which may be secured in place by screws or other suitable fastening devices. That end of the level through which the pocket 15 opens is bound about by a strip of 75 angle metal 50, the laterally directed flange of which forms guides for a sliding closure 51 which, when in place, bears against the outer end of the cell 45 to hold the same with its spring contacts in engagement with the contacts 38 and 39.

From the foregoing description, taken in connection with the drawings, the operation of my improved level will be readily understood. Under normal conditions, the battery circuit is opened through the switch 35-36. When, however, this switch is closed current passes from the dry cell 85 through the contact 38 and wire 40 and from there branches, one branch passing 90 through the filament of the light bulb 29 to the bracket 27 and through the wire 42 to the bracket 33, through said bracket and the wire 43 to the switch, through the switch and back through the return wire 44 to the 95 battery cell 45. The other branch passes from the contact 23 through the wire 41 to the contact 30 through the burner filament and bracket 33 and wire 43 to the switch and back to the battery cell by the return wire 100 44, both lights being thereby lighted.

With a level constructed in accordance with the above described invention, the bubble tubes may be readily illuminated at any time while holding the level in a natural 105 manner and the requirement for all outside lighting is avoided. As the battery becomes weakened from use it may be removed and replaced by another, none of the connections being loosened as the engagement between 110 the terminals of the battery and the contacts is wholly through the resiliency of said terminals.

Although I have illustrated and described my invention in detail, it will of course be 115 understood that any changes in the details of construction, within the scope of the appended claims, may be made if desired, without in the slightest degree departing from the spirit of my invention.

Having thus described the invention, what is claimed as new is:

1. A level including a parallelepiped shaped body having a bubble tube set in one face intermediate the length of the body 125 and provided adjacent one end with a sight opening and a bubble tube set in the body adjacent the sight opening, said body member being provided at that end opposite the sight opening with a battery receiving 130

- 5 pocket opening through such end and further provided with a straight, continuous and uninterrupted passage leading from such pocket to the sight opening and with
10 5 additional pockets communicating with the passage and located adjacent each of the bubble tubes, electric light bulbs supported in each of the additional pockets to cast their light upon the bubble tubes, conduct
15 10 tor wires leading from the lights through the passage to the battery pocket, said battery pocket, at its inner end, being provided with an extension, a block of insulating material positioned in the extension of the battery pocket and held against movement therein, spaced contacts carried by said block and insulated from each other, the conductor wires being connected to such contacts, a battery mounted in the battery
20 15 pocket and secured against outward movement therefrom, and resilient contacts carried by the battery engaging the contacts of the block and through their resiliency holding the block against outward movement.
25 20 2. An electrically lighted level including
25 a parallelepiped shaped body having a bubble tube set in one face and provided adjacent the bubble tube with a light receiving pocket and adjacent one end with a battery receiving pocket, a battery positioned in its 30 pocket, an internally threaded sleeve mounted in the light pocket and serving as a socket for an electric light bulb, wires leading from the poles of the battery to the light pocket and one connected to the sleeve, 35 and a resilient contact connected to the other wire and engaging against the light bulb, said resilient contact including an arcuate resilient body member, one end of which engages the light bulb and the other end of 40 which carries a laterally directed perforated ear to receive a fastening device by which the contact is secured in place.

In testimony whereof I affix my signature in presence of two witnesses.
